(57) **CLAIM**

The ornamental design for a vase, as shown and described.

DESCRIPTION

FIG. 1 is a perspective view of the invention.

FIG. 2 is a side view thereof. The object is symmetrical in that the front, rear, right and left side views are identical.

FIG. 3 is a top view thereof; and,

FIG. 4 is a sectional view thereof, and is included to more clearly bring out elements of the design.

The bottom thereof is unornamented; a view thereof is therefore omitted.

The broken lines in the drawings represent unclaimed environmental subject matter and form no part of the claim.
